CLAIM

The ornamental design for a therapeutic heart pad, as shown and described.

DESCRIPTION

FIG. 1 shows a perspective view of an assembled therapeutic heart pad;

FIG. 2 shows a front view of the assembled therapeutic heart pad;

FIG. 3 shows a rear view of the assembled therapeutic heart pad;

FIG. 4 shows a right side view of the assembled therapeutic heart pad;

FIG. 5 shows a left side view of the assembled therapeutic heart pad;

FIG. 6 shows a top plan view of the assembled therapeutic heart pad;

FIG. 7 shows a bottom plan view of the assembled therapeutic heart pad;

FIG. 8 shows a front view of the front panel of the therapeutic heart pad;

FIG. 9 shows a rear view of the front panel of the therapeutic heart pad;

FIG. 10 shows a right side view of the front panel of the therapeutic heart pad;

FIG. 11 shows a left side view of the front panel of the therapeutic heart pad;

FIG. 12 shows a top plan view of the front panel of the therapeutic heart pad;

FIG. 13 shows a bottom plan view of the front panel of the therapeutic heart pad;

FIG. 14 shows a front view of the back panel of the therapeutic heart pad;

FIG. 15 shows a rear view of the back panel of the therapeutic heart pad;

FIG. 16 shows a right side view of the back panel of the therapeutic heart pad;

FIG. 17 shows a left side view of the back panel of the therapeutic heart pad;

FIG. 18 shows a top plan view of the back panel of the therapeutic heart pad; and,

FIG. 19 shows a bottom plan view of the back panel of the therapeutic heart pad.

1 Claim, 8 Drawing Sheets
